US00D681650S

(12) **United States Design Patent**
Fletcher et al.

(10) Patent No.:

US D681,650 S

(45) Date of Patent: ** May 7, 2013

(54) **DISPLAY PANEL WITH GRAPHICAL USER INTERFACE FOR ANALYZING AND PRESENTING SUPPLY, FABRICATION AND LOGISTICS DATA**

(75) Inventors: **Tom Fletcher**, San Jose, CA (US); **Ed Hancock**, Penfield, NY (US); **Payton Patterson**, Collierville, TN (US); **Eoghan Maher**, Cork (IR); **Akhil Oltikar**, San Diego, CA (US)

(73) Assignee: **Flextronics AP, LLC**, Broomfield, CO (US)

(**) Term: 14 Years

(21) Appl. No.: 29/410,227

(22) Filed: Jan. 5, 2012

(51) LOC (9) Cl. 14-04

(52) U.S. Cl.

USPC D14/485

(58) **Field of Classification Search** D14/485-495;

(57) **CLAIM**

The ornamental design for a display panel with graphical user interface for analyzing and presenting supply, fabrication and logistics data, as shown and described.

DESCRIPTION

The FIGURE depicts a display panel with graphical user interface for analyzing and presenting supply, fabrication and logistics data.

The broken lines in the drawing represent portions of the graphical user interface and the display panel that form no part of the claimed design.

1 Claim, 1 Drawing Sheet
